Application May 31, 1955, Serial No. 36,286

Term of patent 14 years

(Cl. D92—1)

Fig. 1 — 2

Fig. 1 is a plan view of a puffed textile fabric showing our new design, and

Fig. 2 is a sectional view of the fabric of Fig. 1 along the line 2—2.

As shown, the fabric embodying the design is characterized by corrugations extending transversely thereof as shown in Fig. 1, the corrugations are crimped along spaced apart lines which extend vertically of the fabric as shown in Fig. 1, and segments of the corrugations between the lines are depressed centrally thereof.

We claim:

The ornamental design for a puffed textile fabric, as shown and described.
